BINARY CODED TRACK MEANS

Adolfo A. Capanna, Stamford, Conn., assignor to Pitney-Bowes, Inc., Stamford, Conn., a corporation of Delaware

Filed July 14, 1959, Ser. No. 827,066

1 Claim. (Cl. 198—38)

This invention relates to an arrangement useful in the sorting of letter mail, and more particularly, relates to a coding arrangement for effecting the sorting of letter mail among a plurality of separate locations.

The copending U.S. patent application of E. W. Tanguard, Serial No. 786,134, filed on January 12, 1959, now Patent No. 2,970,684 discloses a conveyor which is effective to move a plurality of pockets or receivers in one-by-one succession past a plurality of separate pocket-discharge locations. Pieces of letter mail will be sorted by depositing a letter in each pocket, coding each pocket according to the destination of the letter therein, and causing each pocket to discharge its letter at a correspondingly coded discharge location of a plurality of discharge locations.

According to the disclosed embodiment of the invention, a set of code wheels is provided for each pocket of the conveyor, and the sets of code wheels are moved, concurrently with their respective pockets, in one-by-one succession along a longitudinally extending trackway. The code wheels of each set thereof are individually rotatable about a respective shaft, and each set of code wheels is coded by disposing each code wheel in one of a pair of alternative positions along its shaft.

The longitudinally extending trackway is formed by a plurality of sets of track blocks arranged in longitudinally extending succession. Each set of track blocks comprises three laterally adjacent track blocks. Each track block comprises a single unitary code member having a plurality of laterally adjacent track sections. The track sections of each track block are disposed in only one of each of four pairs of alternative positions whereby each track block is coded to represent a single-digit number from zero through nine.

Each track section of each track block cooperates with one code wheel of each set of code wheels except when a track section is formed by combining into a single track section what would otherwise be two track sections in side-by-side abutting relation. In the case of this latter exception, one track section cooperates, of course, with two code wheels of each set of code wheels.

When at least one code wheel of any set of code wheels lies in the same alternative position as that of a cooperating track section of any set of track blocks, that code wheel will engage and ride on that track section and the entire set of code wheels will be prevented from descending to an operating or tripping level. When, however, all of the code wheels of any set thereof lie in the respectively opposite alternative positions from those of all of the respectively cooperating track sections of one of the sets of track blocks, none of the code wheels of that set of code wheels will ride on a track section of that set of track blocks and the entire set of code wheels will descend to a tripping level.

Each set of code wheels is so associated with one of the pockets of the conveyor that when a set of code wheels descends to the tripping level, a cam-follower is conditioned to be tripped, thereby to open the associated pocket for the discharge of its contents at a particular one of the discharge locations.

Since each track block represents a single-digit number from zero through nine and since each set of track blocks has three track blocks, each track block set repre-

2

sents a three-digit number from zero through nine hundred ninety-nine. Accordingly, the above-described arrangement of track blocks is capable of accommodating a conveyor having one thousand different discharge locations. It will be apparent then that with only ten different track blocks, one thousand differently coded, three-digit sets of track blocks can be set up. In the manner to be described later in this description, two of the ten different track blocks can be reversed end-to-end so that each can be used to represent two different single-digit numbers. The effect of this is that only eight different track blocks are required to set up one thousand different three-digit combinations. Each track block has its single-digit number indicated thereon whereby selection and assembly of the track blocks can be rapidly, accurately and expeditiously accomplished.

It is accordingly an object of this invention to provide a new and improved coding arrangement for use in effecting the sorting of articles such as pieces of letter mail.

20 A further object of this invention is to provide such a coding arrangement which includes a comparatively small number of differently coded members to accommodate a comparatively large number of different locations among which articles are to be sorted.

25 A further object of the invention is to provide such a coding arrangement whereby selection and assembly of said differently coded members into coded sets, as well as checking of said coded sets, are capable of being rapidly, accurately and expeditiously accomplished.

30 Further objects and advantages will become apparent as the description proceeds.

An embodiment of the invention is shown in the accompanying drawings wherein:

FIG. 1 is a fragmentary plan view broken away in part 35 and showing a longitudinally extending trackway including at least a portion of each of three sets of track blocks according to the invention, along with a set of code wheels on a shaft at the first of the three track block sets where the set of code wheels is being rejected preparatory to subsequent movement of the latter to the second set of track blocks where the set of code wheels will be accepted after which the set of code wheels will be rejected at the third set of track blocks;

FIG. 2 is an end elevational view of said first set of track blocks of FIG. 1 so coded that the set of code wheels shown thereabove are being rejected thereby, the junction between said first set of track blocks and the immediately preceding set of track blocks being shown partly in section;

50 FIG. 3 is a view similar to FIG. 2 but showing said second set of track blocks of FIG. 1, which are coded so as to correspond to the coding of the respective set of code wheels, as having accepted the latter;

FIG. 4 is a view similar to FIGS. 2 and 3 but showing 55 said third set of track blocks of FIG. 1, which are coded differently from the coding of the respective set of code wheels, in the act of rejecting the latter;

FIG. 5 is a sectional view taken along line 5—5 of FIG. 1 and showing a set of code wheels in full lines being rejected and therefore supported by said first set of track blocks, showing that set of code wheels in broken lines at a second position at which it has been accepted by said second set of track blocks, and showing that set of code wheels in broken lines at a third position at which it is being supported by auxiliary means while passing from said second set of track blocks to said third set of track blocks;

FIG. 6 is a schematic diagram showing ten groups of 70 code wheels coded in succession from left to right to represent the ten single-digit numbers consecutively from zero through nine, the four binary 0 positions being indicated by dot-dash lines, the value of each code wheel in

its binary 1 position being indicated thereon, and the number represented by each group of code wheels being indicated thereabove.

Referring particularly to FIGS. 1, 2 and 5, there is shown a set of twelve code wheels generally designated by the reference numeral 20. Each of the code wheels of set 20 is designated by the reference numeral 22 and all of the code wheels of this set are carried by a shaft 24 for rotation thereabout. Shaft 24 has twenty-four peripheral grooves 26, two for each code wheel. Taking the right-hand groove of the pair of grooves for each code wheel, as viewed in FIGS. 1 and 2, to be at a binary 0 (zero) position, the left-hand groove of each pair will be at a binary 1 (one) position. Shaft 24 also carries a plurality of split-ring stops 28 which separate the respective pairs of grooves 26 so that, when each code wheel 22 is in its binary 0 position, it will be retained by a groove 26 and will engage a stop 28 at its right-hand side and, when in its binary 1 position, each code wheel 22 will be retained by a groove 26 and will engage a stop 28 at its left-hand side. By way of example, the code wheel 22 at the far left-hand side of each of FIGS. 1 and 2 has its right-hand side engaging a stop 28, and this code wheel is therefore in its binary 0 position. The twelve code wheels 22 of set 20 are in three groups of four code wheels each, and each group of code wheels represents a single-digit number from zero through nine. As indicated in FIG. 4, the right-hand group represents the units digit, the center group the tens digit, and the left-hand group the hundreds digit. Starting from the right-hand side of each group of code wheels as viewed in FIG. 2, the first code wheel has a value of one when in its binary 1 position; and, when in their binary 1 positions, the second code wheel has a value of two, the third a value of four, and the fourth a value of eight. (The four code wheels of each group will hereinafter be so referred to as the first, second, third and fourth code wheels, respectively.) When any code wheel 22 is in its binary 0 position, it has a value of zero. The sum of the values of all of the code wheels of each group is equal to the single-digit number represented by that group. When all of the code wheels 22 of any group thereof are in their binary 0 positions as shown by the group of code wheels labelled 0 in FIG. 6, the number represented by that group will be zero. When only the first code wheel of a group is in its binary 1 position as shown by the group of code wheels labelled 1 in FIG. 6, the number represented by that group will be one. Similarly, the second wheel, when shifted to its binary 1 position, adds the value of two to the total value of its group. To represent the number three, the first and second code wheels of a group are shifted to their binary 1 positions as shown by the group of code wheels labelled 3 in FIG. 6. It will be apparent that the ten different values from zero through nine can be set up in this manner, all as indicated in sequence from left to right in FIG. 6. By way of example, the set of code wheels 20 as shown in each of FIGS. 1-4 has been coded to represent the number three hundred fifteen since only the first and second code wheels of the hundreds digit group have been shifted to their binary 1 positions, only the first code wheel of the tens digit group has been shifted to its binary 1 position, and only the first and third code wheels of the units digit group have been shifted to their binary 1 positions.

The set of code wheels 20 as described above represents one of a plurality of identical but individually coded sets of code wheels which are moved in one-by-one succession along a longitudinally extending trackway by a conveyor. For additional details of the sets of code wheels, and for the details of a conveyor for so moving the code wheels sets, reference is hereby made to the above-cited copending patent application of E. W. Tangard.

The longitudinally extending trackway mentioned above will now be described. Referring particularly to FIGS. 1, 2 and 5, the illustrated embodiment of the invention includes a longitudinally extending track bed 29 supported

by a pair of angular frame members 31, 33, these frame members being, in turn, supported by the frame of the conveyor.

Retained on track bed 29, by means later to be described, are a plurality of code members in the form of track blocks having the reference numerals 30, 32, 34, 36, 38, 40, 42 and 44, respectively. Each track block is a single unitary piece including a base 46 and a plurality of transversely spaced projections or track sections 48 and 50. It will be noted from FIGS. 1-4 that each track section 50 has a width substantially twice that of each of track sections 48. Each track section 48 of each track block cooperates with one code wheel 22 of each set of code wheels. Each track section 50 of a respective track block is formed by combining into a single track section what would otherwise be two track sections in side-by-side abutting relation. It will be apparent then that each track section 50, having a width twice that of each of track sections 48, cooperates with two code wheels 22 of each set of code wheels. The track sections of each track block lie in only one of each of four pairs of laterally adjacent positions. The eight positions across which each track block extends form a group which corresponds to the eight positions across which each group of four code wheels 22 of each set of code wheels extends. Starting from the right-hand side of each of the track blocks as viewed in each of FIGS. 1 and 2, the first track section of each track block has a value of one when in the binary 0 position; and, when in their binary 0 positions, the second track section of each track block has a value of two, the third track section of each track block has a value of four, and the fourth track section of each track block has a value of eight. This is in contradistinction to the code wheels in that each code wheel, as noted above, has a value other than zero only when it is in the opposite binary position, namely, the binary 1 position. It follows that each track section, when in its binary 1 position, has a value of zero. In common with the code wheels of each group of four thereof, each track block has each of its track sections lying in the right-hand one of its pair of alternative positions when in the binary 0 position and in the left-hand one when in the binary 1 position.

Each track block represents a single-digit number from zero through nine. Taking the track block 30, one of which is disposed at the lower left corner and one at the upper right corner of FIG. 1, all of track sections 48 thereof are in their binary 1 (left-hand) positions. The total value of this track block 30, which is equal to the single-digit number represented by this track block, is therefore zero. Only the first track section of track block 38 lies in its binary 0 position whereby this track block represents the number one. The double-width track section 50 of track block 34 lies in the two positions which would otherwise be those occupied by two separate, abutting, single-width first and second track sections, with only the second track section in its binary 0 position whereby this track block represents the number two. Only the first and the second track sections 48 of track block 36 lie in their binary 0 positions so that this track block represents the number three. The double-width track section 50 of track block 32 lies in the two positions which would otherwise be those occupied by two separate, abutting, single-width second and third track sections, with only the third track section in its binary 0 position. This track block 32 therefore represents the number four. Track blocks 40, 42 and 44 follow this same pattern to represent the numbers five, six and eight, respectively, as shown in FIG. 1. It will be noted that track block 38, which represents the number one as shown in each of FIGS. 1 and 2, can be reversed end-to-end to represent the number seven. Also, track block 42, which represents the number six as shown in each of FIGS. 1 and 2, can be reversed end-to-end to represent the number nine. Furthermore, each of track blocks 36 and 40 is symmetrical about a central, longi-

tudinal, vertical plane so that each of these two track blocks represents the same respective number when reversed end-to-end.

Each of the track blocks has its respective single-digit number indicated thereon. Each of the track blocks is molded of rubber or other noise-dampening material, and the number represented by each track block is marked thereon by raised or depressed marks in the mold. Each track block has its number indicated thereon at its trailing end with respect to the direction of movement of the respective sets of code wheels 20 as indicated by the direction-of-movement arrow adjacent the lower left corner of FIG. 1. Each of track blocks 36, 38, 40 and 42 is marked at both of its opposite ends to indicate the number represented thereby when reversed end-to-end. An arrow is marked adjacent the number indicated on each track block thereby to indicate that the respective number should be read with the arrow adjacent thereto pointing to a cam track 52 later to be described.

The track blocks are arranged in successive, transversely extending sets respectively designated generally by the reference numerals 54, 56 and 58, and, as shown in each of FIGS. 1-4, there are three track blocks to each set thereof. As shown in FIG. 1 and respectively in FIGS. 2, 3 and 4, track block set 54 is coded to represent the three-digit number zero forty-two, track block set 56 is coded to represent the three-digit number three hundred fifteen, and track block set 58 is coded to represent the three digit number six hundred eighty. It will be apparent that each track block set can be coded to represent any one of the one thousand three-digit numbers from zero through nine hundred ninety-nine. The conveyor, of course, provides a separate discharge location for each set of track blocks.

A filler strip 60 of material such as steel is disposed on track bed 29 in abutting relation between the bases 46 of the track blocks of each two successive sets thereof. As is apparent from FIG. 1, the base 46 of each of the track blocks extends longitudinally a greater distance than the track sections thereof to provide a shoulder at each end thereof. A plurality of headed bolts 62, each having an integral flange 64 adjacent its head, extend through aligned apertures in each filler strip and in track bed 29 into threaded engagement with respective nuts 66. The flange 64 of each bolt 62 overlaps the respective shoulders of the track blocks between which it lies, whereby the track blocks are rigidly held in their respective positions on track bed 29 when the nuts 66 are tightened down. Each of filler strips 60 carries an integral cross-piece 68 at one end to aid in retaining each of a plurality of cam track pieces 70 in accurately spaced relation to the adjacent track blocks.

All of cam track pieces 70 are identical with each other and lie in successive, longitudinally extending, mutually abutting relation to form the continuous cam track 52. Each of cam track pieces 70 is secured in place against a cross-piece 68 and on track bed 29 by means of screws 72, each of the latter extending through aligned apertures in frame member 33 and track bed 29 into tightened threaded engagement with a respective cam track piece 70. Cam track 52 includes a channel formed, in part, by two upstanding side walls 74, 74. As exemplified by the code wheel set 20 as shown in the drawing, the shaft 24 of each of the successive sets of code wheels carries a cam follower roller 76 of the same diameter as that of each of the code wheels 22. Each cam follower roller 76 is laterally fixed on its shaft 24 by means of a pair of split rings 78, 78 for rotation about its shaft. Each cam follower roller rides between side walls 74, 74 and is guided thereby against substantial lateral movement whereby each set of code wheels is guided laterally as it moves along the trackway.

The bottom of the channel formed by cam track 52 is formed, in part, by successively alternate upper and lower cam dwell surfaces 80 and 82, respectively, as shown in

FIG. 5. Cam dwell surfaces 80 and 82 are interconnected by gradually sloping cam surfaces 84 and 86 respectively. As shown in FIG. 5 and as described more in detail in the above-cited copending application of E. W. Tangard, the shaft 24 of each set of code wheels is carried by a pair of laterally spaced brackets 88 (only one of which is shown in FIG. 5) for pivotal movement about a respective main shaft 90. Each main shaft 90 is moved by the conveyor along the trackway at a constant level relative thereto. As indicated by FIG. 5, an upper cam dwell surface 80 is disposed laterally adjacent the longitudinally space between each two longitudinally adjacent sets of track blocks to retain each set of code wheels in raised relation above the tripping level described above. A lower cam dwell surface 82 is disposed laterally adjacent each set of track blocks and longitudinally between the ends of the track sections of each set of track blocks. When at least one of the twelve code wheels 22 of any set thereof is disposed in the same binary position as that of its cooperating track section of any set of track blocks, that code wheel will ride on that track section, thereby preventing the cam follower roller 76 of that code wheel set from riding down a gradually downwardly sloping cam track surface 84. The result is that that entire set of code wheels will be prevented from descending pivotally about its main shaft 90 to the tripping level. When, however, all twelve code wheels 22 of any set thereof are disposed in the respectively opposite binary positions from those of their cooperating track sections of any set of track blocks, that set of track blocks will permit the cam follower roller of that code wheel set to ride on a downwardly sloping cam surface 84 and then on the succeeding lower cam dwell surface 82. The result is that that set of code wheels will descend, under the weight of the code wheels 22 and shaft 24, pivotally about the respective main shaft 90 to the tripping level.

The code wheels 22 of the code wheel set 20, as shown in each of FIGS. 1-4, are coded to represent the number three hundred fifteen. Track block set 54, as shown in each of FIGS. 1 and 2, is coded to represent the number zero forty-two. This being the case, the first, second and third code wheels of the units digit group, the first and third code wheels of the tens digit group, and the first and second code wheels of the hundreds digit group (all of code wheel set 20) will be in the same binary position as their respectively cooperating track sections of track block set 54. Each of these named code wheels will therefore ride on its cooperating track section thereby preventing that code wheel set from descending to the tripping level. This condition is depicted in FIG. 5 wherein certain of the code wheels 22 (in the full-line positions) are riding on cooperating track sections 48 thereby preventing the cam follower roller 76 from riding on upwardly sloping cam surface 86 of cam track 52. Track block set 56, as shown in each of FIGS. 1 and 3, is coded to represent the same number as that to which code wheel set 20 has been coded, namely, three hundred fifteen. Therefore, all of the code wheels 22 of set 20 will be in the opposite binary positions from those of their respectively cooperating track sections of track block set 56 whereby code wheel set 20 will descend pivotally about main shaft 90 to the tripping level under the control of cam follower roller 76 as the latter rides on downwardly sloping cam surface 84. See FIG. 5. Code wheel set 20 remains in the tripping position as cam follower roller 76 rides on lower cam dwell surface 82 (see the first broken-line position of code wheel 22 in FIG. 5) and is returned to the non-tripping level by the succeeding upwardly sloping cam surface 86. As is the case between each two succeeding sets of track blocks, cam follower roller 76 rides on an upper cam dwell surface 80 while moving across the space adjacent the junction between the track block sets 56 and 58 (see the second broken-line position of code wheel 22 in FIG. 5). Track block set 58 is coded to represent the

number six hundred eighty whereby the first and third code wheels of the units digit group, the first and fourth code wheels of the tens digit group and the first and third code wheels of the hundreds digit group (all of code wheel set 20) will ride on their respectively cooperating track sections, with the result that the code wheel set 20 is rejected by track block set 58 and does not descend to the tripping level.

As brought out in the general description above and as described in detail in the above-cited patent application of E. W. Tangard, when any one of the sets of code wheels descends to the tripping level the letter-carrying pocket associated therewith discharges its letter at the proper one of a plurality of different discharge locations. In this manner, sorting of the letter mail is accomplished. It will be obvious that articles other than letter mail, such as sheets, cards, etc., can be sorted in the same manner. Setting of the code wheels 22 to their coded positions on shaft 24 can be accomplished by means of the device shown and described in my copending U.S. patent application Serial No. 800,891, filed on March 20, 1959, now Patent No. 2,979,183.

From the above description and the accompanying drawings, it will be apparent that the present invention provides the above-stated objects and other advantages. Setting up of the trackway is accomplished by simply picking out, among only eight different track blocks, the three appropriate track blocks of each set of track blocks; assembling the track block sets in succession, along with filler strips 60, on the track bed 29; and securing the track block sets in place by tightening down nuts 66 on headed screws 62. Only eight different track blocks being required, and the number represented by each track block being indicated thereon; selection of the correct blocks, assembly thereof into as many as one thousand different track block sets, and checking of the assembled track blocks are rapidly, accurately and expeditiously accomplished. Because only eight different track blocks are required to represent the ten single-digit numbers from zero through nine, only eight corresponding molding dies are required to mold all of the different track blocks.

Since many changes could be made in the embodiment

of the invention as particularly described and shown herein without departing from the scope of the invention, it is intended that this embodiment be considered as exemplary and that the invention not be limited except as warranted by the following claim.

5 What is claimed is:

A binary-coded assembly adapted to accept or reject each of a plurality of successively presented, individually coded sets of code elements; said assembly comprising a 10 longitudinally extending track bed; a plurality of sets of unitary track blocks arranged on said bed in longitudinally extending succession; the track blocks of each of said sets lying on said bed in laterally adjacent relation to each 15 other and transversely of a plurality of longitudinally-extending positions of a plurality of laterally adjacent pairs of laterally adjacent, alternative positions arranged in a plurality of groups; each of said track blocks including a base and a plurality of transversely spaced projections lying in only one of the alternative positions of all 20 of the pairs of one of said groups to represent a selected single-digit number whereby each of said projections, when lying in a position coinciding with the position of a code element of any one of said sets thereof, engages that code element to reject that set of code elements and 25 otherwise permits acceptance of that set of code elements; the base of each track block extending longitudinally a greater distance than the projections thereof to provide a shoulder at each end thereof; a filler strip secured between and engaged with the respective bases of the track blocks 30 of each two succeeding sets of track blocks; means secured in overlapping relation with the mutually adjacent shoulders of the track blocks of the succeeding sets thereof to retain said track blocks on said track bed; and each of said track blocks having its selected single-digit number indicated thereon.
